NOTE PAPER HOLDER

Esther Graham, Dallas, Tex.

Application November 16, 1939, Serial No. 304,824

7 Claims. (Cl. 281—7)

This invention relates to stationery and more particularly to an improved holder for use in connection with a memorandum sheet or stenographic note paper.

An object of this invention is to provide a device of this kind including an inclined table or support and means for selectively moving a sheet of paper along the table or support during the writing on the paper exposed on the table.

Another object of this invention is to provide a structure of this kind including a supply roll positioned between a pair of side walls, and beneath a table and means for winding the strip of paper from the supply roll onto the other roll, the strip of paper passing over the top of the table.

Another object of this invention is to provide a structure of this kind including an improved means for detachably holding a pair of rollers beneath the writing table together with an improved means for rotating at least one of the rolls in order to wind the paper thereabout from the other roll.

A further object of this invention is to provide, in a structure of this kind, an improved means for rotatably supporting a pair of rollers beneath the writing table in order that the rollers may be readily removed or replaced.

A still further object of this invention is to provide in a structure of this kind an improved rotating means for rotating the strip of paper on one of a pair of rollers, the rotating means being so mounted that it may be engaged with either one of a pair of rollers.

With the foregoing and other objects in view, which may hereinafter appear, the invention consists of such parts and such combination of parts as will be specifically referred to and illustrated in the accompanying drawings, wherein is shown an embodiment of the invention, but it is to be understood that changes, variations and modifications may be resorted to which fall within the scope of the invention, as claimed.

In the drawings:

Figure 1 is a fragmentary perspective view of this invention;

Figure 2 is a perspective view of the ruled guide used with the structure shown in Figure 1;

Figure 3 is a detail side elevation, partly broken away, of a modification of this invention;

Figure 4 is a detail side elevation, partly broken away, and in section, of a further modification of the invention;

Figure 5 is a horizontal section, partly in fragmentary detail looking from the inside of the

drive shaft mounting means used with Figures 3 and 4.

Figure 6 is a fragmentary horizontal section of a further modification of this invention;

Figure 7 is an enlarged fragmentary horizontal section of the roller operating shaft shown in Figure 6; and

Figure 8 is a fragmentary horizontal section of a further modification of this invention.

With reference to Figures 1 and 2, there is disclosed a frame or supporting structure including side walls 59 and a table 60. A crank or operating member 61 is rotatably carried by each side wall 59, and is adapted to rotate an associated roller positioned between the two side walls 59. Where paper is used which is not ruled, the writing may be guided transversely of the strip by means of a ruled sheet member 62 provided with a plurality of parallel lines 63 on the upper surface thereof. This sheet 62 may be made out of cardboard or the like, and is adapted to be movably held on the table 60 by means of lower clips or clamping members 64 and upper clips or clamping members 65. These clamping members 64 and 65 are substantially U-shaped and have a portion thereof overlying table 60 so that the card or guide member 62 may be shifted laterally of the table in order to either remove or replace the guide beneath the clamping members 64. Resilient feet or cushion members 66 are secured to the opposite ends of each side wall 59 so as to frictionally hold the device against movement during the use thereof.

In Figure 3 there is disclosed a modification of this invention including a pair of side walls 67 and a top wall 68. A pair of rollers 69 and 70 have associated therewith driven gear members 71 and 72 respectively. A selected gear 71 and 72 may be rotated by means of a driving gear 73 carried by a drive shaft 74 having a crank or handle 75 secured thereto. The crank or handle 75 is adapted to be positioned exteriorly of the adjacent side wall 67.

In Figure 5 there is disclosed a means whereby the driving gear 73 may be shifted forwardly or rearwardly to engage either the gear 71 or the gear 72. In order to accomplish this the side wall 67 is provided with an elongated slot 76 and a substantially U-shaped spring 77 having outwardly flared opposite end portions, 78 and 79 formed with the spring 77. The wing member 78 is adapted to be secured in any desired manner to the side wall 67. These wing members 78 and 79 extend upwardly and outwardly relative to the slot 76 and resiliently hold the shaft 74 in a se-

lected end of the slot 76. The bight portion of the U-member 77 is disposed substantially adjacent the lower longitudinal edge of the slot 76, as shown in Figure 5.

5 The side members 67 are each provided with a pair of rubber feet or cushion members 80 which are adapted to frictionally hold the device against movement on a plane surface.

In Figure 4 there is disclosed a further modification of this invention wherein a frame or supporting structure is provided including side walls 81 and a top wall or table 82. A pair of rollers 83 and 84 are rotatably supported between the side walls 81 and the roller 83 is provided with 10 a driven gear 85. The roller 84 is provided with a driven gear 86 and an intermediate gear 87 is rotatably carried by a shaft 88 secured to a side wall 81. The gear 87 is adapted to be in constant mesh with the gear 85. A driving gear 89 is 15 secured to a drive shaft 90 having a crank 91 fixed thereto. The shaft 90, is adapted to project through the slot provided in a side wall 81 similar to the slot 76 shown in Figure 5, and it will be understood that the structure shown in Figure 5 20 will apply equally as well for the drive shaft 90 as for the drive shaft 74. In this manner the driving gear 89 may be moved either rearwardly to mesh with the driven gear 86, or may be moved forwardly to mesh with the intermediate gear 87.

25 Referring now to Figures 6 and 7 the numerals 152 and 153 designate side walls of a modified form of this invention and the numerals 154 and 155 designate a pair of spaced apart stub shafts which are carried by the wall 152. A gear 156 is fixedly mounted on the stub shaft 154 and a second gear 157 is fixedly mounted on the stub shaft 155. This structure is similar to the structure shown in Figure 3. A spring pressed pivot member 158 is slidably through the side wall 153, being provided with a plate or head 159 which is engageable with a roller 160. A spring 161 bears at one end against the plate 159 and at the other end against the inner face of the side wall 153. The pivot member 158 is provided with a head or knob 162 on its outer end so that the pivot member 158 may be manually pulled outwardly so as to release the roll 163 from the pivot member 158 and from the shaft 154 which is journaled through the wall 152. A roll 163 is detachably connected at one end to the shaft 155 on which the gear 157 is secured and the opposite end of the roll 163 engages the inner end of a pivot member 164 which extends through the side wall 153. The pivot member 164 is provided with a head or coupling member 165 on its inner end which engages against the roll 163 and the spring 166 urges the pivot member 164 inwardly into contact with the roll 163. A knob 167 is carried by the outer end of the pivot member 164.

60 An operating shaft 168 extends between the two side walls 152 and 153 between the rolls 160 and 163, being mounted at one end in a bearing structure 169 carried by the side wall 153. The bearing structure 169 includes, as shown in Figure 65 7, an opening 170 which will permit slight angular adjustment of the shaft 168 at the opposite end thereof. The shaft 168 is provided with a crank or handle 171 outwardly of the side wall 153 and a second crank 172 is secured to the opposite end 70 of the shaft 168. The opposite end of the shaft 168 extends through an elongated opening or slot 173 provided in the wall 152, and a spring 174, similar to the spring 77, engages the shaft 168 so as to hold this shaft against either end of the opening or slot 173. A driving gear 175 is secured

to the shaft 168 and in one position of the shaft 168 the gear 175 is adapted to mesh with the gear 157. This is the position shown in full lines in Figure 6. In the opposite position the gear 175 is adapted to mesh with the gear 156. In this 5 manner the drive shaft 168 can be coupled with either gear 156 or 157 so as to permit winding of the paper on either roll 160 or 163. The use of the two cranks 171 and 172 also permits the rotation of the shaft 168 by either hand of the 10 operator.

In Figure 8 there is disclosed a further modification of this invention which is somewhat similar to the disclosure shown in Figure 4. In this modification a drive shaft 176 extends through the side walls 177 and 178 and a crank 179 is secured to one end of the shaft 176 and a similar crank 180 is secured to the opposite end of the shaft 176. A gear 181 is secured to a shaft 182 journaled in the side wall 178 and a roll 183 is 20 adapted to be coupled with the shaft 182. A spring pressed shaft 184 extends through the side wall 177 being provided with a coupling head 185 on its inner end and a spring 186 engages at one end against the head 185 and at the other end 25 against the inner face of the side wall 177. A knob 187 is secured to the shaft or pivot member 184 on the outer end thereof. A second gear 188 is secured to a shaft 189, journaled in the side wall 178 and a roll 190 is coupled to the shaft 189. 30

A spring pressed pivot member 191 engages through the side wall 177 being provided with a coupling head 192 on its inner end and a spring 193 bears at one end against the head 192 and at the other end against the inner surface of the 35 side wall 177.

An idler gear 194 is mounted on a shaft 195 carried by the side wall 178 and is in constant mesh with the gear 188. A driving gear 196 is secured to the drive shaft 176 and in one position 40 of the shaft 176 the gear 196 is adapted to mesh with the idler gear 194. In another position of the shaft 176 the driving gear 196 is adapted to mesh with the gear 181. The means for shifting or holding the shaft 176 in either a forward or 45 rearward position is similar to the structure shown in Figure 5, and also in Figure 7.

With a structure as hereinbefore described the roll of paper can be used on one side thereof, for the entire length of the strip, and, after one side 50 of the paper has been used the roll can be readily turned around so as to use the opposite or reverse side of the paper.

What I claim is:

1. A device as set forth comprising a support 55 including a pair of side walls, an inclined table between said walls, a pair of rollers disposed between said walls, means rotatably supporting said rollers beneath said table, and an adjustable bodily shiftable spring held driving means common to and for selectively driving said rolls.

2. A device as set forth comprising a support including a pair of side walls, a downwardly offset table between said walls, a pair of rollers disposed between said walls, means rotatably supporting said rollers beneath said table, and an adjustable bodily shiftable spring held driving means common to and for selectively driving said rolls, said driving means being supported by and operated exteriorly of said walls. 70

3. A device as set forth comprising a support including a pair of side walls, an inclined table between said walls, a ruled writing guide member engaging on said table, upper and lower clips carried by said support and engaging said guide 75

member, a pair of rollers rotatably carried by said side walls beneath said table, and an adjustable bodily shiftable spring held driving means common to and for selectively driving said rolls, said driving means being slidably supported by and operated exteriorly of said walls.

4. A device as set forth comprising a pair of triangularly shaped side walls, a top wall secured between said side walls, a pair of rollers between said side walls, a pair of parallel stub shafts rotatably carried by one of said side walls, a gear fixed to each stub shaft, said one side wall having an elongated slot therein, a drive shaft extending through said slot, yieldable means for holding said drive shaft at a selected end of said slot, a driving gear fixed to said drive shaft, a crank fixed to said drive shaft and a second pair of stub shafts alining with said first pair of stub shafts, said driving gear being engageable with a selected stub shaft gear.

5. A device as set forth comprising a pair of triangularly shaped side walls, a top wall secured between said side walls, a pair of parallel stub shafts rotatably carried by one of said side walls, a pair of gears fixed one to each stub shaft, an intermediate gear rotatably carried by said one side wall and meshing with one of said pair of gears, said one wall having an elongated slot therein, a drive shaft extending through said slot, yieldable means holding said drive shaft at a selected end of said slot, a driving gear fixed to said drive shaft and adapted to selectively mesh with said intermediate gear or the other of said pair of gears, and a crank fixed to said shaft.

35 6. A device as set forth, comprising a housing formed of triangularly shaped side walls, a top wall secured between said side walls and inclined to the horizontal, a pair of parallel stub shafts

rotatably carried by one of said side walls, a gear fixed to each stub shaft, spring-pressed pivot means carried by the other side wall in alignment with said stub shafts and engageable with a pair of paper rolls for coupling said rolls to said stub shafts, a drive shaft extending between said side walls in substantially parallel relation to said stub shafts, said one side wall having an elongated slot through which an end of said drive shaft loosely engages, a driving gear fixed to said drive shaft, yieldable means fixed to said one side wall and engaging said shaft to selectively hold said shaft with said driving gear in mesh with one of said pair of gears, and a crank at each end of said drive shaft.

7. A device as set forth, comprising a housing formed of triangularly shaped side walls, a top wall secured between said side walls and inclined to the horizontal, a pair of parallel stub shafts rotatably carried by one of said side walls, a gear fixed to each stub shaft, spring-pressed pivot means carried by the other side wall in alignment with said stub shafts and engageable with a pair of paper rolls for coupling said rolls to said stub shafts, a drive shaft extending between said side walls in substantially parallel relation to said stub shafts, said one side wall having an elongated slot through which an end of said drive shaft loosely engages, a driving gear fixed to said drive shaft, an idler gear rotatably carried by said one side wall and constantly meshing with one of said pair of gears, yieldable means fixed to said one side wall and engaging said shaft to selectively hold said driving gear in mesh with either said idler gear or the other of said pair of gears and a crank at each end of said drive shaft.

ESTHER GRAHAM.
